KALEIDOSCOPE

Joseph Gordon, 220 S. Carondelet St.,
Los Angeles, Calif. 90057

Filed Dec. 13, 1967, Ser. No. 9,766

Term of patent 3½ years

(Cl. D34—15)

FIG. 1.

FIG. 2.

FIG. 3.

FIG. 4.

FIG. 1 is a front perspective view of a kaleidoscope showing my new design;

FIG. 2 is a front elevational view thereof;

FIG. 3 is a top plan view thereof; and

FIG. 4 is a right elevational view.

A typical kaleidoscope pattern is depicted in broken lines in FIGS. 1 and 2.

I claim:

The ornamental design for a kaleidoscope, as shown and described.
